UNITED STATES PATENT OFFICE

2,509,781

APPLE CELLING AND SLICING MACHINE

John W. Pease, deceased, late of Rochester, N. Y.,
by Winnifred N. Pease, executrix, Rochester,
N. Y.

Application January 19, 1948, Serial No. 3,125

3 Claims. (Cl. 146—40)

1

The present invention relates to machines for seed-celling and slicing apples and like fruits.

In the preparation of apples for cooking, canning and drying it is customary practice to first pare and core the apples. Then the apples are fed into a combined seed-celling and slicing machine for removal of the seeds and seed-cells and for quartering the apples or dividing them into lesser divisions.

In seed-celling and slicing machines, it is conventional practice to provide a rotary spindle, to one side of which the culling knife is secured. Mounted radially of this spindle are the slicing blades which are located just beneath the culling knife. The cored apples are dropped over the rotating spindle and guided by their cored holes to the slicing blades. An oscillating arm or beam, which is adapted to straddle the spindle, serves to seat each apple against the slicing blades so that its seed-cells will register axially with the culling knife. The slicing blades enter partly into the apple and serve to hold it against rotation in a partially severed condition while the seed-cells are being removed. After culling, another apple is dropped onto the rotating spindle, and the movement of this apple into seed-celling position by the oscillating arm or beam serves to push the first apple through the slicing blades; and thus the operation of the machine is completed.

The slicing blades only enter partially into an apple prior to the seed-celling operation, but even this partial entrance slightly weakens the apple and may result in the apple being split prematurely under the slightly expanding pressure of the culling knife at its center. Moreover, the falling apple may be shattered by its impact against the slicing blades. These mischances are particularly possible if the apple happens to be unusually soft and mellow. If the apple is split prematurely it is usually broken up into a lot of unusable fragments.

One object of the present invention is to provide means for holding an apple during culling which will prevent the apple from being broken into segments under the expanding pressure of the culling knife.

Another object of the invention is to provide means for preventing premature splitting of an apple which will also serve as auxiliary means for holding the apple against rotation during seed-celling.

A further object of the invention is to provide means for easing the fall of an apple as it drops down the rotating seed-celling spindle, so as to prevent the slicing blades from being embedded

2

by gravity too deeply into the apple or from shattering the falling apple.

Another object of the invention is to provide means which will so retard the fall of the apple that the actual positioning of the apple axially prior to the seed-celling operation will be wholly controlled by the oscillating arm or beam, thereby insuring more accurate centering of the apple for seed-celling.

10 Other objects of the invention will be apparent hereinafter from the specification and from the recital of the appended claims.

In the drawings:

Fig. 1 is a side elevation of a seed-celling and slicing machine in which are incorporated the features of the present invention, the machine being shown broken away at the bottom and partly in vertical section and the feeding platform and positioning arm or beam being shown at the 20 end of a cycle of operation;

Fig. 2 is a side elevation on an enlarged scale of the culling knife and the adjacent parts of the culling spindle;

Fig. 3 is an enlarged view taken at right angles 25 to the view of Fig. 1, with parts broken away, and showing an apple dropping down the spindle to culling position;

Fig. 4 is a section on the line 4—4 of Fig. 3 looking in the direction of the arrows;

Fig. 5 is a fragmentary view similar to Fig. 3 but showing an apple in seed-celling position;

Fig. 6 is an enlarged view of parts shown in Fig. 5, showing how the apple is held during the seed-celling operation;

Fig. 7 is a fragmentary enlarged view showing 35 one set of holding blades;

Fig. 8 is a plan sectional view showing the relative positions of the slicing spider, apple holding means and culling knife and spindle; and

Fig. 9 is a view showing these parts with an 40 apple in seed-celling position.

Referring now to the drawings more particularly, 10 denotes the frame of the machine which is substantially rectangular and made of angle iron. The frame is covered at its top by a tray 11 which is preferably slightly forwardly inclined. It is upon this tray that the cored apples are spread or piled ready to the hand of the operator.

At an intermediate height there is supported 50 in the frame of the machine a spider 12 (Figs. 8 and 9) which is secured to the frame 10 by screws or bolts 14. This spider is provided with a central opening in which is mounted a ring 15 which is provided with a plurality of slicing blades which extend radially from a common center. The

slicing ring is secured to the spider 12 by screws 17.

The slicing ring is provided with two sets of slicing blades. The blades of the two sets alternate with one another and are denoted at 16 and 18, respectively. The blades 16 have their inner ends higher than their outer ends (Fig. 6) and are inclined downwardly from their inner ends to their outer ends, while the blades 18 are inclined upwardly from their inner ends to their outer ends. The inner ends of all the blades are fixed in a stationary sleeve 19.

This sleeve is supported by ribs 20 of a casting 21 which is secured by screws or bolts 22 (Fig. 3) to cross-beams of frame 10. Rotatably mounted in the sleeve 19 is a rotary spindle 25. The upper free end of this spindle projects into a well 26 (Fig. 1) which is near the lower or front end of the tray 11 and which surrounds an opening 23 in the tray through which an apple may be placed upon the spindle. The spindle is provided intermediate its ends with an enlarged portion 27 (Fig. 2), which terminates in a shoulder 28 that rests upon the sleeve 19. The spindle itself is flattened off at its bottom at one side as denoted at 29 in Fig. 2 and is connected by a set screw 30' (Fig. 3) to the bevel miter gear 31. This gear meshes with and is driven by a bevel miter gear 32 which is secured by a screw 33 to a horizontal shaft 34. The shaft 34 is journaled in the casting 21 and has collars 35' and 36' secured to it by set screws 37' and 38'. These collars engage against the bearings for the shaft 34 to prevent axial movement of the shaft. The shaft is adapted to be driven during operation of the machine by a sprocket or pulley 38 which is secured by a set screw 39 to the shaft.

The enlarged portion 27 of the spindle has a flat part 30 to which is secured the rigid seed-celling knife 35. This knife projects laterally from the spindle and is bowed or semicircular in shape. It is narrower at its top than at the bottom and is inclined slightly upwardly in a direction opposite to the direction of rotation of the spindle. Thus, while a cored apple is sliding down on the spindle, the knife 35 makes an imperceptible track or channel in the core opening thereof without further mutilation of the apple despite the continuous rotation of the spindle.

40 (Fig. 1) denotes the vertically swinging feed-arm or beam which serves to locate the apple axially for seed-celling. This arm is pivotally mounted at 41 upon the frame of the machine. It has a fork or bifurcation 42 at its free end which is adapted to straddle the spindle 25 in the movement of the arm. The arm is adapted to be oscillated up and down by a cam 44 which is secured to a shaft 45 that is journaled in a bracket 49 which is secured to frame 10. The throw of the arm 40 can be adjusted precisely by adjustment of a set screw 46 which threads into the arm and engages a strap 47 that is secured at one end to the arm by a screw or rivet 48. This strap engages the periphery of the cam 44.

While one apple is being celled, another apple is prevented from dropping onto the first by a platform 50. This platform is also adapted, when in operative position, to straddle spindle 25. It is carried by an arm 51 that is continuously biased towards operative position by a coil spring 52. The loop of this spring surrounds a pin 53 which is secured in the frame and opposite ends of it engage the arm 51 and an arm 54, respectively. The arm 54 is secured to a bar 55 that is fastened to the frame. The arm 51 has a follower 56 at its inner end that engages in the

trackway of a cam 57 which is secured to the shaft 45. The shaft 45 is driven continuously during operation of the machine from a shaft 60 through a spur pinion 61 and a spur gear 62, the latter being secured to the shaft 45.

The arm 40 is normally urged upwardly by a coil spring 65 which is secured at one end to an angle plate 66 that is fastened to the frame of the machine and at its opposite end to an arm 67 which is secured by bolts 68 to beam arm 40.

All of this is conventional structure in seed-celling and slicing machines.

Secured to a cross bar of the frame of the machine are two brackets 70 and 70' (Figs. 3 and 5). Pivotedly mounted upon these brackets are the arms 72 and 72'. Secured to opposite sides of the lower end of the arm 72 by screws 74 are two plates 75 and 75a. These plates have legs parallel to the sides of arm 72 and laterally extending wings which are disposed angularly to the legs and which project at opposite sides of the arm. The laterally extending wings have their tops rolled over, as denoted at 78 in Fig. 7. Welded, or secured in any other suitable manner to the upright portions of the wings are holding blades 76. Secured to the lower end of the arm 72' by screws 74' are similar plates 75' and 75'a', respectively (Figs. 8 and 9) which also have blades 76 fastened in them.

The wing portions of plates 75, 75a, 75' and 75'a form an approximately hollow square, see Figs. 8 and 9, with the knife blades 76 projecting inwardly. The square arrangement allows the wings to accommodate themselves to the shape of the apple whether regular or irregular and the holding blades 76, when engaged with the apple prevent it from being broken into segments prematurely under the expanding pressure of the culling knife. The plates 75 and 75a and 75' and 75'a constitute, therefore, opposed jaws having sharp edges 76 for securely holding an apple during seed-celling.

Secured to the inside surfaces of the arms 72 and 72' above the plates are spring arms or straps 80 and 80'. The straps 80 and 80' are secured to the arms 72 and 72', respectively, in opposed relation by screws 81. They serve to limit the drop of the apple under the effect of gravity and prevent it from becoming impaled on the slicing blades 16 until the arm 40 in its action positively seats it on these blades, thereby accurately centering it with reference to the culling knife 35.

The arms 72 and 72' are adapted to be constantly urged toward one another under the action of coil springs 82 and 82' (Figs. 3 and 5). These are secured at one end to pins 83 and 83', respectively, and at their opposite ends to pins 84 and 84', respectively. The pins 84 and 84' are threaded into the arms 72 and 72'. The pins 83 and 83' are secured in the casting 21. Stops 85 and 85', which are secured in the plates 70 and 70', respectively, serve to limit the inward movement of the arms 72 and 72' by engagement with the pins 84 and 84', respectively.

65 The arms 72 and 72' are adapted to rock about pivot studs or bolts 86 and 86' (Figs. 3, 4 and 5). They are held against the plates 70 and 70', respectively, by coil springs, one of which is shown at 87 in Fig. 4. The spring is interposed between a washer 88 and one face of the arm 72. Tension of the spring can be adjusted by the nut 89 which threads onto the pivot bolt 86.

The faces of the plates 70 and 70', which contact the arms 72 and 72', are convex. The convex surface of plate 70 is denoted at 90 in Fig. 4.

The hole bored in each arm 12, 72' for the pivot stud 86 or 86' is double conical in shape. The bore of arm 72 is denoted at 92 in Fig. 4. This construction together with the convex contacting surfaces of the plates permits the arms to rock to accommodate themselves to apples of various sizes and shapes.

The operation of the machine will be understood from the preceding description, but may briefly be summed up here.

When the machine is in continuous operation, there is always an apple resting on the slicing blades 16, as shown at A in Figs. 1 and 6, except for those instantaneous intervals when an apple is actually being pushed through the slicing blades 16 and 18. At such times, the forked platform 50 is in operative position (Figs. 1 and 5) straddling the spindle 25 and holding a second apple B from falling down the spindle on which it has just been placed by the operator.

For the first operation of the machine on a new lot of apples, the operator places a cored apple over the top end of spindle 25 on forked platform 50. This spindle and the shaft 45 are rotating all the while. At a predetermined point in the rotation of the cam 57, the arm 51 is swung laterally to swing the platform 50 aside (Fig. 3), allowing the apple to drop down the spindle. At this time, the arm or beam 40 will be in its uppermost position as shown in Fig. 3.

As the apple drops down the spindle, its movement will be retarded by the spring arms 80 and 80' and it will be prevented from falling onto the knife blades 16 by gravity. The cam 44 in its rotation will now cause the arm 40 to move downwardly to engage the apple A and move it down to the culling position. This position can be accurately gauged by adjustment of the strap 47 so that the apple will be correctly centered axially with reference to the seed-celling knife 35 under control of the arm 40. There is no chance, as has happened with machines of previous design, that gravity may drop the apple down so far that it cannot be properly centered. Continued rotation of the cam 57 meantime will restore the arm 51 to the position shown in Fig. 1 to support the next apple B which the operator has placed upon the spindle 25.

The action of arm 40 will seat the first apple A securely on the slicing blades 16 and the holding blades 76 will take firm hold of it in line with the point of action of the seed-celling knife. Thus the apple will be held firmly against rotation as the rotating culling knife 35 performs its function. Moreover, the inward pressure exerted by springs 82 and 82' on holding plates 75, 75a, 75' and 75'a and blades 16 will offset and counteract any outward pressure due to action of the culling knife; and thus, the apple will be prevented from splitting or disruption.

The arm 40 remains down during seed-celling with the fork 42 straddling the spindle 25 and just touching the apple A. When the high-point of the cam 44, which is rotating in the direction of the arrow 95 (Fig. 1), has rotated out of contact with the strap 47, the arm 40 rises under influence of the spring 65, and, as seed-celling on the first apple A is completed, the cam 57 will rotate to such a position as to swing the arm 51 laterally to release the second apple B.

As the apple B slides down the spindle it will be retarded by spring arms 80 and 80' and settle gently on top of apple A. Cam 57 will now restore platform 50 to operative position to support the next apple, while cam 44 will cause arm 40 to

move downwardly to engage apple B and force that apple down to culling position. The apple B pushes Apple A ahead of it through the slicing blades 16 and 18, and apple B assumes the culling position formerly occupied by apple A.

The movement of apple A through slicing blades 16 and 18 completes the operation thereon and its pieces are deflected into a suitable receptacle by the sheet metal deflectors 97 (Fig. 1). The machine continues in operation and the cycle of seed-culling and slicing is completed for apple B and for all the other apples of the lot as described for apple A.

While the invention has been described in connection with a particular embodiment thereof, it is capable of further modification, and this application is intended to cover any variations, uses, or adaptations of the invention following, in general, the principles of the invention and including such departures from the present disclosures as come within known or customary practice in the art to which the invention pertains and as may be applied to the essential features hereinbefore set forth and as fall within the scope of the invention or the limits of the appended claims.

Having thus described the invention, what is claimed is:

1. In a seed-celling and slicing machine, the combination with a vertically disposed rotary spindle having a free upper end for impalement of cored apples thereon, a seed-celling knife secured thereto, and a plurality of slicing blades extending radially of said spindle and mounted below said knife, of a pair of pivotally mounted arms disposed at opposite sides, respectively, of said spindle, each of said arms carrying a jaw, the two jaws being adapted to engage an apple from opposite sides thereof to hold the apple against rotation during operation of the knife, each of said jaws having a blade thereon which extends generally axially of the spindle, and means for resiliently pressing said arms toward the spindle to hold the jaws in operative position, of a resilient finger mounted on each arm, said fingers being disposed at opposite sides of the spindle and above said jaws to retard an apple falling down said spindle, means for rotating said spindle, and means adapted to straddle said spindle to push a cored apple through said resilient fingers to seat the apple on said slicing blades and between said jaws, said last-named means being operable through the intermediation of a second apple to push the first apple through said slicing blades when positioning the second apple between said jaws.

2. In a seed-celling and slicing machine, the combination with a vertically disposed rotary spindle, a seed-celling knife secured thereto, and a plurality of slicing blades extending radially of said spindle and mounted below said knife but close enough thereto to engage an apple while the seed-celling knife is operating on the apple, of auxiliary means for holding the apple during operation of said knife comprising a pair of jaw members disposed above said slicing blades and opposite the seed-celling knife and adapted to grip an apple from opposite sides thereof to hold said apple against disintegration during operation of said knife, each of said jaw members having two jaw faces, projections on the interiors of said faces for biting into an apple to grip the same, means for rotating said spindle, means for moving said jaw members into apple-engaging position, and means for forcing an apple through

said slicing blades after the seed-celling operation is completed.

3. In a seed-celling and slicing machine, the combination with a vertically disposed rotary spindle having a free upper end for impalement of cored apples thereon, a seed-celling knife secured thereto, and a plurality of slicing blades extending radially of said spindle and mounted below said knife but close enough thereto to engage an apple while the seed-celling knife is operating on the apple, of auxiliary means for holding the apple during operation of said knife comprising a pair of pivotally mounted jaws disposed at opposite sides of said spindle and adapted to engage an apple from opposite sides thereof to hold the apple during action of said knife, of a pair of resilient fingers disposed at opposite sides of said spindle and above said jaws to retard an apple falling down said spindle, and means adapted to straddle said spindle to push a cored apple through said resilient fingers to seat the apple on said slicing blades and between said jaws, 10

5 said last-named means being operable through the intermediation of a second apple to push the first apple through said slicing blades when positioning the second apple between said jaws, some, at least, of said slicing blades having their inner ends higher than their outer ends and extending upwardly between the jaws.

WINNIFRED N. PEASE.
